1,653,078

UNITED STATES PATENT OFFICE.

FRED H. WINTER, OF SCHENECTADY, NEW YORK, ASSIGNOR TO GENERAL ELECTRIC COMPANY, A CORPORATION OF NEW YORK.

RELAY.

Application filed January 12, 1927. Serial No. 160,729.

My invention relates to improvements in relays, and more particularly to improvements in differential relays which function in accordance with the relative values of two electric quantities.

In certain automatic reclosing circuit breaker arrangements, such as disclosed for example in German Patent 398,017 of July 3, 1924, corresponding to application for Letters Patent of the United States, Serial No. 571,183, filed June 27, 1922, in the name of A. E. Anderson, and assigned to the same assignee as this invention, the reclosing of the circuit breaker is made responsive to the ratio of the voltage of the supply circuit to the voltage across a current limiting device connected across the line terminals of the circuit breaker. In such cases, the reclosing relay used for the comparison of these voltages may be of the balanced or differential type. The relay comprises actuating and restraining electromagnets, the windings of these electromagnets being connected to be energized respectively in accordance with the supply circuit voltage and the voltage across the current limiting device. So long as the line is fed from but one end, operation of the relay on a substantially definite ratio basis is readily attainable. However, if the line is or may be fed from both ends, then a reversal of current may occur in the winding connected across the current limiting device; that is to say, the winding of the restraining electromagnet. Consequently, the resultant magnetic fields of the relay differ in accordance with the direction in which the line is fed. Operation at the desired ratio does not occur in each case, due, I believe, to the difference in the effect of the leakage flux of the actuating electromagnet on the restraining electromagnet because of their proximity. While this difference might be avoided by spacing the electromagnets so far apart as to eliminate this stray field interference effect, the reclosing relay would be considerably larger and, therefore, necessitate additional switchboard space. This, in many cases, so increases the cost as to be economically prohibitive.

An object of my invention is, therefore, to provide an improved differential relay whereby this objectionable difference in action arising from a change in the direction of the current in one of the windings, whatever the cause, whether leakage flux or other-

wise, is compensated without increasing the size of the relay.

My invention will be better understood from the following description when considered in connection with the accompanying drawing, and its scope will be pointed out in the appended claims.

The single figure of the accompanying drawing illustrates diagrammatically an embodiment of my invention in a differential relay comprising two separate but relatively closely spaced electromagnets 1 and 2, which are arranged to exert opposing forces on a movable member 3. This member comprises two magnetic parts such as armatures 4, one for each electromagnet, rigidly secured to an intermediate non-magnetic part such as a piece of Bakelite 5 which is pivoted at 6. For circuit controlling purposes, the member 3 is provided with a contact 7 which may be flexibly mounted as shown and which is arranged to cooperate with a contact 8. This contact may be adjustably positioned as shown.

Each of the electromagnets 1 and 2, hereinafter termed respectively the actuating and restraining electromagnets, is provided with a magnetic circuit comprising a magnetic core 9, a magnetic member 10 and one of the armatures 4. The parts 11 and 12 are merely supporting pieces of non-magnetic material. The actuating electromagnet 1 further comprises an actuating winding 13 and may also be provided with a holding or sealing-in winding 14 which is connected in circuit with the contacts 7 through the lead 15 so as to be energized when the contacts 7 and 8 are closed. The restraining electromagnet 2 comprises a restraining winding 16 and means such as a winding 17 for compensating for the difference in the effect of the electromagnets 1 and 2 on the member 3 due to a change in the direction of the current in the restraining winding 16. This compensating winding 17 is connected to be energized proportionately to the energization of the actuating winding 13 since it is to compensate for the effect of the leakage flux thereof on the restraining electromagnet 2. For this purpose it is connected in circuit with the actuating winding 13 and as shown in series therewith. In order to adjust the relay for operation on the occurrence of a predetermined relation of currents in the actuating

and restraining windings 13, 16 as for example when the ratio of the current in the actuating winding 13 to the current in the restraining winding 16 exceeds a predetermined value, the cores 9 are adjustably mounted as shown and there are provided suitable biasing means, preferably adjustable, such as springs 18 and an adjustable stop 19 for the member 3 whereby the position of the member 3 when the restraining electromagnet 2 is predominant and, therefore, the relative air gaps of the armatures 4 for any given position of the cores 9 is determined.

In the illustrated embodiment of my invention, if the restraining winding 16 is energized by a current flowing in the direction indicated by the arrow 20, and the actuating and compensating windings 14 and 17, respectively, are energized by a current flowing in the direction indicated by the arrow 21, then the fluxes due to the restraining and compensating windings are cumulative. If, however, the direction of the current in the restraining winding is as indicated by the arrow 22, then the fluxes due to the restraining and compensating windings are in opposition. With this arrangement, I have found it possible, with the restraining winding 16 energized and the member 3 turned clockwise until the armature 4 of the actuating electromagnet 1 is against the stop 19, to move the member 3 counterclockwise to circuit closing position upon energizing the actuating winding 13 by a current which bears a definite ratio to the current in the restraining winding 16, irrespective of the direction of the current in the restraining winding. I attribute this to the fact that the effect of the leakage flux from the actuating electromagnet 1, not passing through the armatures 4, on the restraining electromagnet 2 is compensated by the electromagnetic action of the winding 17.

While relays embodying my invention are particularly applicable to automatic reclosing circuit breaker arrangements such as disclosed in the patent and patent application heretofore referred to, their use is not so limited. When applied to such arrangements so as to effect the reclosing of the circuit breaker when the ratio of the supply circuit voltage to the voltage across the current limiting device connected across the circuit breaker exceeds a predetermined value, the restraining winding 16 is connected across the current limiting device as heretofore, and the actuating and compensating windings are arranged to be connected across the supply circuit on one side or the other of the circuit breaker after it has opened; these two windings being connected as the actuating winding has been heretofore.

While I have shown and described my

invention in considerable detail, I do not desire to be limited to the exact arrangements shown, but seek to cover in the appended claims all those modifications that fall within the true spirit and scope of my invention. 70

What I claim as new, and desire to secure by Letters Patent of the United States, is:

1. A relay comprising a movable member and means for controlling the movement thereof comprising two separate, relatively closely spaced electromagnets arranged to exert opposing forces on the member and to move the member from one position to another when the windings of the electromagnets are energized by currents having a predetermined relation, and means for compensating for the difference in the effect of said electromagnets on said member due to a change in the direction of the current in the winding of one of the electromagnets comprising a winding on one of the electromagnets arranged to be energized proportionately to the energization of the winding of the other electromagnet. 80 85

2. A relay comprising a movable circuit controlling member and means for controlling the movement thereof comprising actuating and restraining electromagnets spaced relatively closely and arranged to exert opposing forces on the member and to move the member to circuit closing position when the currents in the windings of the electromagnets have a predetermined relation, and means for compensating for the difference in the effect of said electromagnets on said member due to a change in the direction of the current in the winding of the restraining electromagnet comprising a winding thereon connected in circuit with the winding of the actuating electromagnet. 90 95 100 105

3. A relay comprising a movable member and means for controlling the movement thereof comprising actuating and restraining electromagnets spaced relatively closely and arranged to exert opposing forces on the member and to move the member from one position to another when the ratio of the current in the winding of the actuating electromagnet to the current in the winding of the restraining electromagnet exceeds a predetermined value, and means for compensating for the difference in the effect of said electromagnets on said member due to a change in the direction of the current in the winding of the restraining electromagnet comprising a winding thereon connected to be energized proportionately to the energization of the winding of the actuating electromagnet. 110 115 120

4. A relay comprising a movable member and means for controlling the movement thereof comprising actuating and restraining electromagnets spaced relatively closely and arranged to exert opposing forces on the member and to move the member from one 125 130

position to another when the windings of the electromagnets are energized by currents having a predetermined relation, and means for compensating for the difference in the effect of said electromagnets on said member due to a change in the direction of the current in the winding of the restraining electromagnet comprising a winding thereon connected to be energized proportionately to the energization of the winding of the actuating electromagnet.

5. A relay comprising a movable circuit controlling member and means for controlling the movement thereof comprising actuating and restraining electromagnets spaced relatively closely and arranged to exert op-

posing forces on the member and to move the member to circuit controlling position when the ratio of the current in the winding of the actuating electromagnet to the current in the winding of the restraining electromagnet exceeds a predetermined value, and means for compensating for the difference in the effect of said electromagnets on said member due to a change in the direction of the current in the winding of the restraining electromagnet comprising a winding thereon connected in series with the winding of the actuating electromagnet.

In witness whereof, I have hereunto set my hand this 11th day of January, 1927.

FRED H. WINTER.
